UNITED STATES PATENT OFFICE.

JULES MARIE XAVIER TERLINDEN, OF BRUSSELS, BELGIUM.

ROTARY ENGINE.

SPECIFICATION forming part of Letters Patent No. 271,156, dated January 23, 1883.

Application filed September 22, 1882. (No model.) Patented in Belgium March 17, 1882, No. 57,377; in England August 19, 1882, No. 3,992, and in France August 28, 1882.

To all whom it may concern:

Be it known that I, JULES MARIE XAVIER TERLINDEN, a Belgian subject, residing at Brussels, in the Kingdom of Belgium, a retired superior officer of the Belgian army, knight of the order of Leopold, have invented new and useful Improvements in Rotary Engines Applicable as Motive-Power Engines or as Pumps, (for which I have obtained a patent in Belgium, No. 57,377, bearing date the 17th of March, 1882, and for which application for Letters Patent has been made in England on the 19th of August, 1882, No. 3,992, and in France on the 28th of August, 1882,) of which the following is a specification.

My invention relates to that class of rotary engines in which radial pistons or vanes slide to and fro in slots formed in a drum or hub mounted eccentrically in a cylinder or casing; and it consists in the improvements, hereinafter described, by which the required motion is given to the pistons or vanes, and the sides and ends of the said pistons or vanes are caused to work fluid-tight in the cylinder or casing. I attain these objects by the mechanism illustrated in the accompanying drawings.

Figure 1 is a cross-section, and Fig. 2 an elevation, of a rotary motive-power engine constructed according to my invention. Fig. 3 is a front elevation of part of one of the pistons. Fig. 4 is an end view of the same. Fig. 5 is a cross-section through the line E F. Fig. 6 is horizontal section through the line C D. Fig. 7 is a horizontal section through the line A B. Fig. 8 is a horizontal section through one of the covers of the cylinder or casing. These figures—from 3 to 8, inclusive—are made upon a somewhat larger scale than Figs. 1 and 2. Fig. 9 represents in cross-section, and Fig. 10 in longitudinal section, a portion of the engine, and show another way in which the parts can be constructed. Figs. 11 and 12 are details showing metal bands, hereinafter described. Figs. 13 and 14 respectively represent in cross-section and longitudinal section my engine applied as a pump. Figs. 15, 16, 17, and 18 are details, respectively, showing sectional views of the piston, as hereinafter described.

Within a suitable cylinder or casing, *a*, pro-

vided at each end with a suitable cover, *h*, and upon an axis, *a*², traversing the said covers eccentrically to the center of the said cylinder or casing *a*, I mount a cylindrical revolving drum, *b*, so that a part of its outer surface is constantly in contact with a part of the inner surface of the cylinder *a* or a metal plate, *x*, inserted therein, and adjustable by means of a set-screw or otherwise.

In the drum *b* are four radial slots, *b*', forming slides, in which slide in and out the pistons or vanes *f*, so arranged as to be at their outer ends constantly in contact with the inner surface of the cylinder or casing *a*.

c c are two steam-chambers—one for the inlet and the other for the exhaust of the steam or actuating-fluid. The said chambers communicate with the outside of the cylinder or casing by the pipes *d d'*, and with the inside of the said cylinder or casing by suitable ports, as seen in Fig. 1. The two chambers *c c* together present somewhat the figure of a crescent divided in the middle and separated from the interior of the cylinder or casing by suitable partitions, as shown in Fig. 1, and, according as the actuating-fluid is caused to enter at *d* or *d'*, one or the other of the said chambers *c* will be for the inlet of the said fluid and the other for the discharge of the same.

Two of the said engines *a a'* are placed end to end, as seen in Figs. 1 and 2, (the parts of the engine *a'* being shown in dotted lines in Fig. 1.) Each of the engines may be actuated separately and be worked at the same pressure; or the steam or fluid from one of the cylinders may be caused to pass into the second cylinder, to act expansively therein. In both cases the engines will be caused to work continuously, uniformly, and regularly, for, the pistons or vanes of one of the engines being set at an angle of forty-five degrees to those in the other engine, the unequal velocities imparted to the shaft by each of the drums equalize each other eight times and compensate each other eight times during each revolution of the drums. The reaction of the second engine on the first engine diminishes the effect of the latter in case of the steam or other fluid being used expansively, as hereinbefore described, thus tending to equalize the action of both engines.

A two-way cock, *e*, enables the steam or fluid to be cut off as required, or the motion of the engine to be reversed.

When regularity of motion is not required 5 a single engine may be used instead of two, as hereinbefore described, such single engine being provided with two, three, or four pistons or vanes. The said engine being symmetrical, the pistons or vanes may be caused to revolve 10 in either direction, according as the steam or fluid enters at *d* or at *d'*, or as the drum *b* is mounted upon its axis.

I will now proceed to describe the arrangement for causing the drum *b* and pistons or 15 vanes *f* to work fluid-tight against the covers of the cylinder *a*, and for causing the outer ends of the said pistons or vanes *f* to work fluid-tight against the inner surface of the cylinder or casing *a*, and also for causing the said pistons or vanes *f* to slide in and out of the slots 20 *b'*, as required.

In order to make the ends of the drum work fluid-tight with the covers of the cylinder, each of the ends of the drum is covered 25 by a disk, *g*, affixed to it, Figs. 3 and 8, a part of the said disks *g* being made to enter and work in a depression formed to receive it in the covers *h*.

In order to make the ends of the pistons or 30 vanes work fluid-tight with the inner surface of the cylinder or casing *a*, the outer end of each of the said pistons or vanes *f* is formed with a cavity or groove, in which fits a metal roller or tube, *i*, (which may be solid or hollow.) The said roller or tube *i* projects upward slightly above the end of the piston or vane, and is capable of partial rotation therein. It also projects beyond the sides of the piston or vane, and the projecting ends of the 35 said roller or tube fit each into a circular groove, *j*, formed in the covers *h*, the width of the said groove being rather less than the full diameter of the said roller or tube. The said grooves *j* serve as guides to the pistons or vanes, causing 40 them to slide in and out of their slots *b'* during the rotation of the drum *b*, so as to keep their ends constantly in intimate contact with the inner surface of the cylinder or casing *a*. The upper parts of the rollers or tubes 45 *i* are throughout their length, at *k*, Fig. 4, curved to the radius of the cylinder or casing *a*, and at their opposite side, at *l*, where they enter the grooves *j*, they are curved concentrically. The reduced diameter of the roller 50 or tube at *k* and *l* enables the ends of the said roller or tube to engage in the said grooves *j*. If it be desired to increase the contact of the ends of the roller or tube *i* with the groove *j*, the ends of the tube *i* may be fitted with a separate plug or end piece, *i'*, Figs. 3 and 7, arranged so as to be pressed outward by the action 55 of the steam or fluid.

The sides of the pistons or vanes *f* are made to work fluid-tight against the covers of the 60 cylinder or casing *a*, as follows: On each side of the piston or vane is a slot or channel, in which slides a plate of suitable metal, *m*. One

end of the said plate *m* rests upon the body of the piston or vane at *m'*, Fig. 3. Its other end bears against the roller or tube *i*. Behind 70 the slot or channel in which slides the plate *m* is a steam-passage, *n*, opening into the slot *b'*.

In the middle of the length of the piston or vane *f*, and just below the roller or tube *i*, is formed a passage, *o*, Figs. 5 and 6, in which 75 is mounted a double-acting valve, *p*. The valve *p*, being pressed upon by the steam or fluid on one side of the piston or vane *f*, opens one of the apertures *o'* *o''* and closes the other. The steam or fluid enters the passage *o*, passes up 80 into the tube *i*, where it presses the plugs or end pieces, *i'*, into the grooves *j*, and, passing down the said passage *o*, enters the slot or slide *b'*, presses forward the piston or vane *f* against the inner surface of the cylinder or 85 casing, and, entering the passages *n*, presses the plates *m* against the cylinder-covers.

In Figs. 9 and 10, *a* is the outer cylinder or casing; *b*, the rotary drum, formed with slots or slides *b'*, in which the pistons or vanes slide. 90 The said pistons or vanes *e* consist of two parts, *c'* *c''*, which work one within the other, like the tubes of a telescope. In some cases the said pistons or vanes may be composed of more than two parts working one within the 95 other telescopically. The admission and discharge of the steam or fluid, instead of being effected at opposite sides of the cylinder or casing, as in Figs. 1 and 2, are effected at *d* *d'*—that is on each side of the point of contact between the drum *b* and cylinder or casing *a*. The pistons or vanes are made semi-cylindrical at their outer ends, with a projecting cylindrical stud at each side, to take into the 100 grooves *e*, and the said studs may be covered by metal ferrules or rings connected together by segmental bands, as represented in Figs. 11 and 12, the said bands covering and protecting the outer end of the piston or vane. The said ferrules and segmental bands may be 105 flattened, as represented at *k* and *l*, Fig. 4. This arrangement is used in substitution for the rollers or tubes *i* represented in Figs. 3, 4, 5, and 7. The bottom of the circular groove *c'* may be provided with a flat annular plate, 110 rendered adjustable by set-screws traversing the cover, or otherwise.

The sides of the drum *b* and of the pistons or vanes in Figs. 9 and 10 are made to work fluid-tight in the cylinder *a* by the covers of 115 the said cylinder or casing being each provided with an inner adjustable cover or plate, *g'*, carried and guided by pins or studs *g''*, projecting from the outer cover, or by other suitable means; and the said inner covers, *g'*, may be 120 adjusted in position, and their contact with the drum *b* and pistons or vanes may be maintained, so as to insure their working fluid-tight, as required, by means of set-screws *h* *h*, or otherwise.

The shaft of the engine rotates directly in the outer covers which are provided with suitable stuffing at *i''* to prevent the escape of steam. The said motive-power engines may 130

be actuated either by steam, air, or any other suitable fluid.

In small engines to be worked at a high speed and to revolve always in the same direction I cause the steam to enter through the drum-shaft. The steam is caused to pass through suitable ports formed in the said shaft and opening into the slots of the drum, where it presses forward the pistons or vanes against the inner surface of the cylinder or casing, and, passing into the said pistons or vanes through suitable passages formed therein, it issues out through suitable openings into the spaces between the pistons or vanes to propel the engine.

Figs. 13, 14 represent in cross-section and in longitudinal section, respectively, the application of my invention to a pump. *a* is the outside cylinder or casing. *b* is the drum, in the slots or slides *c* of which drum two pistons or vanes, *d*, work. *a'* and *a²* are the inlet and outlet passages for the liquid, and *e* is the shaft or axis upon which the drum *b* is mounted. As hereinbefore described with reference to Figs. 1, 2, 3, 4, 5, 6, 7, and 8, the ends of the pistons or vanes *d* are provided with rollers or tubes *i*, (represented in detail, drawn to a larger scale in Figs. 15, 16, and 17.) The ends of the said rollers or tubes *i*, as in the motive-power engine above described, Figs. 3 and 4, project beyond the pistons or vanes, so as to take into the grooves *j*, which act as guides. The said rollers or tubes *i* are closed at their ends by plugs or pistons *i'*, pressed outward by the spiral screw *i²*. The rollers *i* may be made solid instead of being tubular, and the spring *i²* may be dispensed with; or the rollers or tubes *i* may be dispensed with altogether by making the ends of the pistons or vanes of semicircular section, with a cylindrical stud or projection at each end, and covering the ends of the pistons or vanes and the said studs or projections with ferrules or metal rings and segments, as represented in Figs. 11 and 12. If required, a small channel, *l*, Fig. 18, may be made from the outside to behind the pistons or vanes to facilitate the action

of the said pistons or vanes in their slots or slides.

As it is not necessary that the pistons or vanes of pumps should work as perfectly fluid-tight as those of motive-power engines, the sides of the pistons or vanes and of the drum work directly against the covers, as seen in Fig. 14. The cylinder-covers may, however, be provided with adjustable inner covers or plates similar to those represented at *g*, Fig. 10.

In some cases the width of the circular grooves *j* may be equal to the whole length of the piston or vane, which then has the form of a rectangular parallelopiped having on one side a rounded or semi-cylindrical surface and on the other two recesses—one at each end. The parts subjected to friction may be covered with removable pieces of soft metal, as hereinbefore described.

Where the pump is intended to supply small quantities of liquid the piston or vane is simply a roller.

What I claim as my invention, and desire to secure by Letters Patent, is—

1. The combination, with the sliding piston, of the plates *m*, located in grooves in its side edges, and the steam-passages *f*, whereby the steam will force said plates against the ends of the cylinder, substantially as described.

2. The combination, with the sliding piston, of the hollow roller *i*, provided with movable plugs *i'*, and the steam-passages formed in the piston and connecting with the interior of the roller, whereby the expansive force of the steam will force the plugs outwardly, substantially as described.

3. The combination, with the sliding piston provided with passages *n*, *f*, and *o*, and carrying the plates *m*, of roller *i*, and valve *o²*, whereby, when steam is let on, the piston will work tightly within the cylinder, substantially as described.

JULES MARIE XAVIER TERLINDEN.
